UNITED STATES PATENT OFFICE.

HUMBERT DEL VECCHIO, OF WEST NEW YORK, NEW JERSEY.

SAFETY DEVICE FOR PRINTING PRESSES.

Application filed May 31, 1923. Serial No. 642,405.

This invention relates to printing presses, and more particularly, but not exclusively, to that type of press employing reciprocating carriers which receive the printed material or sheets discharged from the printing rolls or plates of the press, and carry them to a discharge point, and aims to provide such presses with safety devices which are adapted to automatically stop such presses the moment a sheet or sheets are caught in the press or fail to be discharged therefrom, with consequent clogging of the press, spoilage of valuable printed material or sheets, danger of fire, damage to the press, the latter resulting in costly delays and tie-ups of the presses, and of the plant of which the press or presses form a part.

It is an object of the invention to provide safety devices of the general character heretofore referred to, and particularly safety devices which shall be simple in construction, inexpensive to manufacture, readily applicable to any press or presses of the class referred to without modifying such press or presses, which shall work with certainty, easy and reliable, which will work in conjunction with the standard equipment of the presses, which shall not easily get out of order or impair in any way the operation of the moving parts of the press or presses, and which possesses other advantages in use to be pointed out hereinafter in the specification.

An illustrative embodiment of the invention will be described in the accompanying specification and shown in the annexed drawings. It is, of course, understood that the invention is not limited to the specific embodiment illustrated and described, since manifestly the same could be changed without in the least departing from the spirit of the invention.

Figure 1 shows a top plan view of the output end of a printing press employing a reciprocating carrier for picking up the printed material discharged from the printing rolls or plates of the press, and carrying such material to the discharge end of the press, together with the device embodying an example of this invention attached thereto.

Figure 2 shows a broken portion of the press in side elevation, with a device form-

ing the subject matter of this invention in place.

Figure 3 is a top plan view of such device shown attached to a cross bar of the press.

Figure 4 is a longitudinal sectional view of the device taken on line 4—4 of Figure 3.

Figure 5 is a cross sectional view of the device taken on line 5—5 of Figure 3.

Figure 6 shows a device embodying a modified form of the invention.

Figure 7 is a longitudinal sectional view of the modified form of the device taken on line 7—7 of Figure 6.

Figure 8 is a cross sectional view of the said modified form of the invention taken on line 8—8 of Figure 7.

Before describing the invention, as illustrated, a brief discussion of the disadvantages and difficulties hitherto encountered in the operation of presses of the class in question will be had. The printing presses employing slidable carriers which pick and carry the printed material or sheets from the printing rolls or plates are provided with a gas burner near the out-put end of the press or presses for the purpose of drying the printed sheets as they are discharged from the press, and for the further purpose of breaking or nullifying the electrostatic charges generated in the material or sheets of paper as they travel along the press and rub against the various parts of the said press.

The flame of this gas burner is exposed in such a manner that it may contact with the printed material or sheets of paper which the carrier carries from the printing side of the press to its discharge end. In fact, in order to break the electrostatic charge in the printed material or sheets of paper, it is necessary that the flame of the burner is applied as near as possible to the printed material.

It frequently occurs that, for many reasons well-known in the printing industries, and especially in those printing plants where the type of presses above referred to, are used, some of the printed material or sheets of paper carried by the carrier fail to be discharged, and as the carrier moves rearwardly toward the rollers or printing plates of the press, to pick up the next printed sheet, the sheet which has failed to discharge is prevented from traveling

with the carrier by certain parts of the printing press, and thereby forced to bulge up. The bulging of a sheet of paper is very disastrous as such occurrence not only destroys 5 that sheet of paper, but also clogs up the machine, preventing the passage and destroying all the other subsequent sheets picked up by the carrier because the first bulged sheet becomes an obstruction in the carrier. Such 10 a clogging is generally known in the printing trade as a congestion. Unless the press is stopped as soon as a congestion starts, the loss of a valuable quantity of printed material may be accompanied by a breakage of 15 certain parts of the press which cannot withstand the pressure of the augmenting mass of congested papers or printed material. Generally, to avoid such congestions, a person or helper is placed at the out-put end of 20 the press who has the duty of watching for congestion and stopping the press when such a congestion takes place, and, of course, outside of the increased cost of the operation of the press, the same, for its successful 25 operation, depends upon the efficiency or deficiencies of such man or helper. But the trouble of a congestion or congestions besides the destruction of valuable material and possible breakage of the machine often times 30 develop into more disastrous results, for the caught material on the carrier is apt to catch fire from the gas burner above pointed out. In fact, in many instances fire resulting from such congestions not only damages the press 35 on which the fire takes place, but endangers also the other parts of the plant of which the press forms a part. The device forming the subject matter of this invention shall entirely 40 eliminate all the above discussed difficulties and disastrous results and besides prolonging the life of the press, diminish the fire hazards to which printing plants are subject, and decrease the cost of operation of the same because the helper required at the out- 45 put end of the press may be dispensed with.

Referring to the aforesaid illustrative embodiment of the invention, and more particularly to the drawing illustrating the same:

In the drawings, a frame 10 conveniently 50 mounts a carriage 11, which is reciprocated back and forth by suitable means 12, said means 12 being connected to an eccentric or a crank moving in conjunction with the rollers or shafts of the press. The foregoing 55 description briefly covers the principal parts of a printing press of the character above referred to, and since the press proper forms no subject matter of the invention only those parts necessary to understand the function of 60 the press is illustrated and described.

On the carriage 11 is mounted a rod 13 which in turn mounts a plurality of guiding fingers 14, which form a stop for the sheet 65 on the carrier, when the carrier receives said sheet, and which slightly swing on their piv-

oted end when the carriage is about to discharge said sheet into a magazine (not shown) purposely provided and arranged below the carrier at the out-put end of the press.

On the said carriage 11 is also mounted a rod 15 which extends parallel with the rod 13 and which mounts a plurality of guiding tines 16, the office of which is that of receiving, spread thereon, a sheet of paper or other material delivered by the straps 17 from the printing rolls or plates of the press. Immediately below the tines 16 and in a position adjacent the forward end of said straps 17, is arranged a third rod 18 which mounts a plurality of detaining fingers 19, the office of which is that of forming an obstruction at the inner edge of the printed material or sheet of paper when the carriage is moving rearwardly for picking the next sheet of paper or material. Hence, by means of the tines 16, the detaining fingers 19 and the guiding fingers 14, the printed material or sheet of paper is picked from the straps 17, and carried toward the rear end of the machine and discharged there on the return stroke of the carriage 11.

The printing presses of the type above referred to are generally provided with a gas burner in the form of a pipe 20 extending 95 adjacent the out-put end of the press and substantially parallel with the rods 13 and 15. By means of this gas burner, the electrostatic charge created in the sheets of paper in their travel along the printing press, and in their rubbing action against the parts of the printing press, is nullified or destroyed by its flame.

Heretofore, a brief description of the printing press has been made and herein-after the device or devices forming the subject matter of this invention will be described. The devices are indicated by the letter A in Figures 1 and 2, and they are secured to the frame of the press, preferably 105 to the stationary cross bar 21, the latter being arranged in the proximity of the rear end of the stroke of the carriage 11.

The illustrated example of the device, as shown more in detail in Figures 3 to 8, inclusive, comprise a bar 30, preferably made of channel or angle iron so as to have a better rigidity, and it is turned upwardly at both ends, as at 31 and 32, so as to present a flaring entry thereunder of the printed material or sheet of paper carried by the tines 16 of the carrier. Intermediate the ends of the said bar, are formed a plurality of openings 33 and at each face of the same are secured by means of rivets or bolts 34, insulating blocks 35 and 36, the material of one of said blocks extending within the openings 33 to the insulating block at the opposite face. Through the insulating blocks and approximately through the center 115 120 125 130

of said openings 33 are formed bores 37, through which extend the shank of slidable elements 38 which may be screws, or bolts, the top end of said screws are preferably 5 threaded and to that end a nut or nuts 39 are threaded. It is here to be noted, that in place of said nuts any other means could be used which instead of being threaded to the shank 38 they can be welded, soldered or 10 otherwise secured to the top end of the slid- able elements. The lower end of the shank of each of said slidable elements 38 are formed with heads or enlargements 69 and between said heads and the insulating block 15 36 at the lower face of the bar 30, is inter- posed an expansion spring 40 which tends to urge each of said slidable elements 38 downwardly. Preferably to the bar 30 may be secured a flexible element or spring 41 20 by means of screws 42 or any other means serving the purpose of said screws. It will be noted that the said flexible element or spring 41 is held at a spaced relation from the bar 30 or the insulating block 36, and 25 that, normally, the heads 69 of the sliding element 38 bear against said spring element 41 for their being moved whenever the spring 41 is deflected. The spring 41 pre- 30 sent a smooth surface at its under side so as to present a smooth surface for the paper or printed material passing thereunder.

On the insulating block 35 I secure, by any approved means, a plurality of conductors 43, preferably in the form of flat strips, 35 which are separated from each other in the vicinity or at the sides of the slidable elements 38, the shanks of said slidable elements are out of contact with said conductors 43 and are normally held in electrical 40 connection with each other by the heads or nuts 39 which bear against them under the actions of spring 40. Hence, when either of the slidable elements 38 are slid upward- 45 ly, by a pressure against the spring element 41, the heads 39 separate from the conductors 43 and therefore the electrical connec- 50 tion therebetween is broken. To the end- conductors on the insulating block 35, I secure, by means of lugs 44, forming a part of 55 said end-conductors, insulating conductors 45 and 46 which are extended to the electrical equipment of the press or of the motor driving the press, as hereinafter more fully described.

55 Most printing presses, and especially those of the type above referred to, are equipped with a Cutler Hammer speed regulating apparatus or switches of a like type made by other manufacturers, of which in 60 addition to the speed regulating character- 65 istics are provided with automatic start and stop means controllable from points remote from the speed regulator. Generally, this is accomplished by placing at different points on the press proper a start end and stop

push button station or box which is electrically connected with the speed regulator controlling the motor driving the press, and by pushing either one button or the other, on the box, the motor is either started or 70 stopped automatically as the case may be. Since this speed regulator and automatic starter and stopper is not part of the invention, no references will be made thereto except by stating that the conductors 45 and 75 46 of the device above described are connected in series with the contacts in the box or station controlling the stopping opera- 80 tion of the speed regulator, so as to place in series with said contacts in the box the separated conductors 43 which, as above 85 pointed out, are normally electrically inter- connected by the heads or nuts 39, and therefore whenever any one of the said nuts or heads are moved away from said conductors, the electrical circuit of the stopper of the speed regulator is broken as if the stop- 90 ping button of the control station on the press was manually pushed to open the cir- 95 990 cuit.

It is thus seen that whenever a sheet of paper or other material fails to discharge and bulges on the tines 16 of the carrier 11, a pressure takes place under the flexible element or spring 41 which in turn presses 95 against the slidable element 38 and forces any one of the heads 39 away from the conductors 43 resulting in a break of the circuit to the stopping control on the speed regulating box. It is here to be noted that 100 the printing press once stopped remains stopped until started manually by pushing the start button, or otherwise, therefore, once the press has been stopped manually, it remains stopped until the operator starts 105 it, as after he has cleared the congestion, assuming that the press has been automatically stopped by the device above described.

In Figures 6, 7 and 8, a modified form of 110 the invention is illustrated, and in this form instead of using slidable contacts, such as contact 38, fixed contacts 50 are employed, all of which are permanently intercon- 115 nected by means of conductors 51 which are led to one of the lead-in wires of a magnet 52. The opposite lead-in wire of the said magnet 52 is connected to a source of elec- 120 trical current 53. The opposite side of said source of electrical current 53 is connected by means of conductor 54 to one of the 125 securing means 42 which hold in place the flexible element or spring 41. The flexible element 41 is normally out of contact with the fixed contact 51 and whenever a bulged paper passes or takes place under the said flexible element 41, the said element deflects upwardly against any one of the stationary contacts 50 and thereby closes the electrical circuit to the magnet 52. The circuit when the flexible element is in contact with any one 130

of contacts 50 is as follows: Out of one side of the source of electrical current 53, through conductor 54 to the flexible element 41, to the stationary contact 50, from the stationary contact 50 to the conductor 51, to one of the lead-in wires of the magnet 52, out of the other lead-in wire of the same magnet, through conductor 55 and back to the source of electrical supply 53. When 10 the magnet is energized, by the closing of the spring element 41 on any one of the contacts 50, the plunger 56 in the electromagnet is forced inwardly, and assuming for a moment that the said electromagnet is arranged adjacent a switch controlling the supply to the motor of the press, the plunger in its inward movement could very well open such switch and stop the motor, or assuming that the electromagnet was arranged 15 near and connected to the mechanical automatic stop with which most of the printing presses are now provided with, the plunger upon its inward movement could very well actuate said automatic mechanical stop as if it had been actuated by hand. But since it is preferable that the motor driving the press is stopped through the regular controls employed in the electrical equipment of the press, it is best to place in 20 the circuit of the stopper of the controller the head or plate 57 carried by the plunger 56 and connected with said circuit by means of conductors 58 and 59 and contact points 60 and 61. When the magnet is de-energized the head 57 under the action of the expansion spring 156 bears on the contact point 60 and 61 and thereby the circuit to the stopper on the controller of the motor is closed, and when the magnet is energized 25 the head 57 moves away from said contacts 60 and 61 against the pressure of spring 156 and the said circuit of the controller stopper is opened and the said stopper on the motor controller actuated. By means 30 of this form of the invention the device may be applied to any stop means now in use in connection with the press and does not limit the device to its connection to the electrical stopper on the speed regulator forming part 35 of the equipment of the press.

Either form of the device is attached to the cross bar 21 by means of the clamp 63 and bolts 64, or any other approved means applicable. The devices are adjustable on 40 the said bar 21 so that their spaced relation with respect to the sheets on the tines 16 may be varied.

I would state, in conclusion, that while the 45 illustrated examples constitute practical embodiments of my invention, I do not limit myself strictly to the exact details herein illustrated, since, manifestly, the same can be considerably varied without departure from the spirit of the invention, as defined 50 in the appended claims.

What I claim as my invention is:

1. A safety device for presses comprising a bar secured to the frame of the press, a stationary electrical contact carried by said bar, a movable contact in coaction with said stationary contact, a flexible element below said electrical contacts, said flexible element being adapted to be moved by a bulged sheet or sheets of material passing thereby, and when so moved moving the movable contacts 70 away from said stationary contacts and leads extending from said contacts to the motor equipment of the press for varying the flow of current passing through the said equipment to the motor driving the press. 75

2. In a printing press, in combination, a bar secured to the frame of the press, a movable electrical contact carried by said bar, a stationary contact also carried by said bar, a flexible element in the proximity of said 80 movable electrical contact for moving the same and conductors connected to said contacts extending to the electrical control box of the press for varying the current in the circuit of said box in response to the movement of said flexible element and movable contact.

3. In a safety device for presses, a bar, clamping means for adjustably clamping said bar to the frame of the press, an insulating block arranged on said bar, stationary electrical contacts carried by said insulating block, said stationary contacts being separated from each other, movable contacts extending between said stationary contacts 95 and normally bridging said stationary contacts and placing them in series with each other, means for moving said movable contacts and conductors connected to the stationary contacts to place the same in circuit 100 with the electrical circuit of the standard electrical equipment of the printing press so that said circuit may become interrupted the moment any of the movable contacts move away from the stationary contacts. 110

4. In a safety device for printing presses, a bar removably and adjustably secured to the frame of the press and presenting at one end, a plurality of openings, a slideable interrupter arranged in each opening, stationary electrical terminals arranged adjacent said openings and conductors connected with said terminals for placing said terminals in series with an electrical circuit controlling the mover of the press for stopping said press when either of said interrupters are moved away from said stationary terminals. 115

5. In a safety device for printing presses having a motor control, a bar detachably secured to the frame of the press, a plurality of conductors spaced from each other carried by said bar, leads for placing said conductors in the electrical circuit of the motor control of the press, and a plurality of 120

125

bridging members normally connecting said conductors in series with each other, said bridging members when a congestion takes place in the press moving away from said 5 conductors break the circuit of the motor control.

6. In combination with a printing press, having an electrical apparatus for controlling the movements thereof and a moving carrier on its output end, of a bar secured to the frame of the press and disposed over the moving carrier, a pair of electrical terminals carried by said bar, one of said terminals being movable in the circuit of said 10 electrical apparatus, and a flexible element between said electrical terminals and the material on the carrier, said flexible element moving said movable terminal away from the other when a sheet or sheets of material 15 bulges on said carrier.

20 7. In a safety device for the motor control of a printing press, a bar having a plurality of holes intermediate its ends, a clamp for adjustably and detachably securing said bar to the frame of the press, an insulating block secured to the upper and lower faces of said bar in the proximity of said holes, said blocks presenting openings in registration with the holes in the bar, a conductor 25 at each end of one of said blocks, separate conductors extending between said openings in the blocks in line with said end conductors, a lead connected to each end conductor, said leads placing said end conductors in the 30 circuit of the electrical control of the press, and said openings in the blocks and carrying bridging members at one end and normally connecting said end 35 conductors and the conductors between 40

openings in series with each other, said slid- 45 able means when moved being adapted to interrupt the circuit of said electrical control of the press.

8. In a safety device for printing presses, having a motor control, a bar, a clamp for securing said bar to the frame of the press, an insulating block carried by said bar, a plurality of separate conductors mounted on said bar, slidable means moving between 50 said conductors and normally connecting one to the other, springs on said slidable means for urging the same in one direction, a flexible element carried by said bar and bearing against one end of said slidable means, 55 said flexible element being moved by the congestion of material taking place in the press and when moved, it moving said slid- 60 able means away from said conductors, and leads placing all of said conductors in series with the electrical circuit of the motor controller of the press, whereby when any one of said slidable means is moved by said flex- 65 ible element, the circuit of said controller is broken.

9. In a safety device for printing presses having a motor control, a plurality of slid- 70 able contacts, a bar mounting said slidable contacts and holding the same adjacent the out-put end of the press so that any bulged sheet of material passing through the press will effect said slidable contacts, a circuit 75 which said slidable contacts are adapted to break when moved, conductors for placing said circuit in the circuit of the controller of the motor driving the press, and means for urging said slidable contacts in the position for closing said circuit.

HUMBERT DEL VECCHIO.
